(57) **CLAIM**

The ornamental design for a transparent storage bin, as shown and described.

DESCRIPTION

FIG. 1 is a right side perspective view of a transparent storage bin showing the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom view thereof;

FIG. 8 is a right side perspective view of a transparent storage bin showing a second embodiment of the design, the sole difference being that the bin has a cover which is transparent in the center and has an opaque rim portion;

FIG. 9 is a front elevational view of the embodiment of FIG. 8;

FIG. 10 is a rear elevational view of the embodiment of FIG. 8;

FIG. 11 is a right side elevational view of the embodiment of FIG. 8;

FIG. 12 is a left side elevational view of the embodiment of FIG. 8;

FIG. 13 is a top plan view of the embodiment of FIG. 8; and,

FIG. 14 is a bottom view of the embodiment of FIG. 8.

The stippling that can be seen on the bottom portion of the claimed design is a type of shading that represents a type of transparent surface.

The broken lines are for the purpose of illustrating the environment of the article only and form no part of the claimed design.
